SUIT HANGER

Rose Waldman, Jersey City, N. J.

Application November 27, 1945, Serial No. 631,058

1 Claim. (Cl. 223—88)

1

This invention relates to suit hangers, and more particularly to a suit hanger upon which a coat and trousers can be hung independently.

When the suit hangers made at present are employed, one of the garments of the suit is positioned over or about the other garment. This nesting of garments prevents the inner garment from being aired, renders difficult its removal, and causes the outer garment to hang unevenly.

Therefore, it is an object of this invention to form a suit hanger upon which the garments can be hung in juxtaposition.

Another object is to form a suit hanger from which either garment can be removed or hung up without disturbing the other garment.

Another object is to form a suit hanger upon which garments can be hung separately instead of in overlapping relationship.

A further object is to form a suit hanger with a trouser hanging element so positioned that the trousers, when hung, can act to retain the front of the coat evenly.

These and other objects are accomplished by forming the suit hanger with an upper and a lower triangular frame, each having two short sides joined together by a long side, the upper frame being suspended at the apex of its short sides by a hook, and the apex of the short sides of the lower frame being suspended from the center of the long side of the upper frame.

Another object is to form a simple, inexpensive suit hanger with a central reinforcing means to bear the weight of the trousers thus eliminating its tendency to collapse the shoulder bearing parts of the coat hanging element.

These and other objects are accomplished by forming the suit hanger with a gripping element having a reinforcing rod and an upper and a lower frame, each frame being formed with a longer base and two shorter sides, and by suspending the apex of the short sides of the upper frame from the gripping element, and the apex of the short sides of the lower element from the base of the upper element and the reinforcing rod, the reinforcing rod extending downward from the apex of the upper frame and being secured to its base.

For further comprehension of the invention, and of the objects and advantages thereof, reference will be had to the following description and accompanying drawings, and to the appended claim in which the various novel features of the invention are more particularly set forth.

In the accompanying drawing forming a material part of this disclosure:

2

Fig. 1 is an elevation of the suit hanger with a suit suspended therefrom.

Fig. 2 is an elevation of the suit hanger shown in Fig. 1 with the suit removed.

5 Fig. 3 is a side view of the hanger shown in Fig. 2.

Fig. 4 is an elevation of a variation of the invention.

10 Fig. 5 is an elevation of another variation of the invention showing a hanger provided with reinforcing means.

Fig. 6 is an elevation of still another variation showing a modified construction of the reinforcing means.

15 In the drawings and in the specification, in which the same numbers represent similar elements, a suit hanger 7, shown in Figs. 1 to 3, incl., is provided with a gripping means 8 made of metal and upper and lower frames 9 and 10 respectively made of plastic, the gripping means 8 is shown in the form of a hook, but if desired can be made in any other suitable form as a clip, button or a hole and pin, etc.

20 The upper frame 9 is formed in a triangular shape with sides or coat rests 11 and 12 and a longer base or rod 13. The gripping means 8 is secured to the frame at the apex of the sides 11 and 12 and the side 13 is positioned opposite the gripping means.

25 30 The lower frame 10 is formed with sides 14 and 15 and a longer base or trouser supporting bar 16. The lower and upper frames are secured together at the intersection of the shorter sides 14 and 15 of the lower frame and the mid-point of the longer side 13 of the upper frame by twist bend 17. The twist bend 17 causes the lower frame to be positioned below the upper frame.

35 40 Although the frames 9 and 10 are shown secured together and positioned by the twist and bend 17, they can also be held together and positioned by a clamp, molded integral with the elements, or by any other suitable means.

45 50 The sides 11 and 12 of the upper frame are capable of supporting a coat, etc. (see Fig. 1), and the side 16 of the lower frame of carrying a pair of trousers. When the suit is placed on the hanger 7, the coat rests in back of the trousers which retain the front of the coat evenly adjacent to the coat back. This relative positioning of the coat and trousers permits either garment to be removed readily without disturbing the other, and likewise permits each garment to be placed upon the hanger independently of each other.

55 56 A suit hanger 18, shown in Fig. 4 is provided

with a gripping means 19 formed integral with an upper frame 20, and a twist bend 17' formed in a slightly different manner from the form shown in Figs. 1-3. Otherwise, the hangers 18 and 1 are similar.

A suit hanger 21, shown in Fig. 5, is provided with a gripping means 22 an upper and a lower frame 23 and 24, respectively. The upper frame is formed with side extending elements 25 suitable for carrying a coat at the shoulders and with a cross bar 26 extending between the ends of the elements 25.

The lower frame 24 is formed with sides 27 and a bar 28 extending between the ends of the sides 27 suitable for suspending a pair of trousers. A rod 29 extending from the gripping means 22 passes through an opening formed at the apex of hanger 21 and downward through a hole 30 in the bar 26, a washer 31, a hole 32 at the intersection of the sides 27 and is provided with an enlarged end or cap 33.

The gripping means 22 and its extension rod 29 together bear the load of the trousers hanging element or frame 24 and relieve the cross bar 26 of all tension, permitting it to act as a stiffening rod and aid in holding the sides 25 in position under their coat load. If desired, the extension rod can be bent out of the plane of the upper frame and then downward.

Although the suit hanger 1 shown in Fig. 1 is described as made of plastic and metal, and the hanger 18 as made of plastic, the hangers can be made completely of either metal, plastic or any other suitable material or combination of materials.

Another suit hanger 34, shown in Fig. 6, is provided with upper and lower frames 35 and 36 respectively, similar to the frames 9 and 10 herefore described and similarly joined to each other by the same twist and bend construction, and gripping means 37. The gripping means 37 has a hooked upper portion 38 extending above the apex of the upper frame, a shank 39 or reinforcing rod passing through an opening 40 in said apex, and a lower hooked portion 41 fitting closely about the twist and bend 42, thus reliev-

ing the cross bar 43 of the upper frame of all tensions under coat loading and permitting it to function as a stiffening rod.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

In a garment hanger for separately supporting a plurality of garments, said hanger comprising a first substantially triangular garment supporting frame having an aperture formed in the apex thereof, a second substantially triangular garment supporting frame having an aperture formed in the apex and base thereof, said apertures of said first and second triangular garment supporting frames being aligned, and the apex of each of said frames extending away from its respective base in the same direction, a rod extending through said aligned apertures whereby said frames may be freely rotatable thereon, means at one end of said rod to prevent said frames from passing thereover, means at the other end of said rod for preventing said frames from passing thereover, said last named means including gripping means.

ROSE WALDMAN.
